Primary Examiner — Lauren D McVey*Assistant Examiner* — Justin A Johnson(74) *Attorney, Agent, or Firm* — Husch Blackwell LLP; Bryan D. Stewart(57) **CLAIM**

The ornamental design for an osteotomy wedge, as shown and described.

DESCRIPTION

FIG. 1 is a perspective view of an osteotomy wedge showing my new design;

FIG. 2 is a top plan view thereof;

FIG. 3 is a bottom plan view thereof;

FIG. 4 is a left-side elevation view thereof;

FIG. 5 is a right-side elevation view thereof;

FIG. 6 is a front elevation view thereof; and,

FIG. 7 is a rear elevation view thereof.

The broken lines illustrate portions of the osteotomy wedge and form no part of the claimed design.
